COMBINATION TRAILER HITCH AND BUMPER GUARD

Ralph H. Swaisgood, Los Angeles, Calif.

Application October 28, 1948, Serial No. 149,356

Term of patent 14 years

(Cl. D14—6)

To all whom it may concern:

Be it known that I, Ralph H. Swaisgood, a citizen of the United States and a resident of Los Angeles, Los Angeles County, California, have invented a new, original, and ornamental Design for a Combination Trailer Hitch and Bumper Guard, of which the following is a specification, reference being had to the accompanying drawing, forming part thereof.

Referring to the drawing:

Figure 1 is a top plan view of a combination trailer hitch and bumper guard, showing my new design;

Figure 2 is an end elevation thereof as viewed from the left of Figure 1;

Figure 3 is a side elevation of the combination trailer hitch and bumper guard;

Figure 4 is an end elevation as viewed from the right of Figure 3;

Figure 5 is a bottom plan view of the combination trailer hitch and bumper guard; and

Figures 6 and 7 are elevational views similar, respectively, to Figures 2 and 3, but with the upper section removed, showing the device as it appears when adapted for use as a trailer hitch.

I claim:

The ornamental design for a combination trailer hitch and bumper guard, as shown.

RALPH H. SWAISGOOD.
